VAPOR STREAM VACUUM PUMP

John W. Tills, Upton, England

Application February 22, 1945, Serial No. 579,178
In Great Britain February 23, 1944

12 Claims. (Cl. 230—101)

1

This invention relates to vapour stream vacuum pumps.

One object is to increase pumping speed.

Another object is to provide a pump which will operate against higher forevacuum pressures than have been usual heretofore.

A further object is to achieve greater reliability of operation with longer intervals between changes or replenishments of working fluid in the system.

Yet a further object is the provision of a pump of robust and durable construction especially suitable for many industrial purposes.

These and other objects will be apparent from the following description of, by way of example, one preferred form of construction illustrated in the drawing annexed hereunto.

In the drawings: Fig. 1 is a side elevation, partly in section, showing a vessel and ancillary parts for working fluid supply and storage; Fig. 2 is a fragmentary detail section, partly in elevation, showing the construction of the vapour stream pump in its relation to the vessel and ancillary parts of Fig. 1; Fig. 3 is a general arrangement in side elevation showing the apparatus complete with backing pump; Fig. 4 is a vertical section of an alternative construction.

A substantially gas-tight steel vessel 10 has a lid 11 gas-tightly secured thereto. An electric motor 12 mounted on a lid 11 drives, by way of a belt 13, a spindle 14 of a stuffing box assembly secured to the wall of vessel 10 so as to partially project therethrough. Spindle 14 is connected through a coupling 15, preferably flexible to a multicylinder piston pump 16. Pump 16 is fed by an inlet pipe 17 and discharges through pipe 18 to a blow-off or pressure release valve assembly 19 supported from the wall of vessel 10 and having an adjustment spindle 20 passing through a stuffing box to atmosphere and terminating in a handwheel 21. A pipe 22 extends between valve assembly 19 and a flange 23 to which it is secured by welding or brazing. Flange 23 is bolted or otherwise secured to the inner side of a pad 24 built into and extending through a wall of vessel 10. A flange 25 to which is attached an end of a pipe 26, is secured to the outside of pad 24. Pipe 26 is connectable by a valve 27 to a pressure gauge 28. A pipe 29 is connectable to a branch of pipe 26 by a valve 30.

Pipe 29 leads from valve 30 to an outer wall 31 of a cooling jacket surrounding a cone shaped body 32 of a vapour stream pump.

One end of a helical conduit 33, which may be of stainless steel, extends through wall of

2

body 32 into the cooling jacket, is supported from the said wall and makes electrical contact therewith. The other end of conduit is connected to, and supports a vapour discharge nozzle assembly 34. A high vacuum connection, to a system (not shown) to be evacuated, is formed by a flange 35 secured by welding or otherwise gas-tightly to the larger diameter end of body 32.

Lid 11 supports a transformer (shown diagrammatically) having a primary winding 36 energizable from the electric supply main or other suitable source and a low voltage (10 volts for example) high current secondary winding 37 one side of which is grounded to the vessel and thence to the pump body 32.

A mechanical backing pump 38, driven by an electric motor 39 has its inlet connected by a forevacuum conduit 40 to a vertical forevacuum chamber 41 mounted substantially gas-tightly on lid 11. The small diameter end of the pump body 32 is connected obliquely to, as a side arm in the wall of chamber 41.

A semiflexible electrical conductor 42, suitably insulated from the inner surfaces of body 32 and chamber 41 extends between so as to connect the ungrounded end of winding 37 with the end of helix 33 near nozzle assembly 34.

In operation a working fluid such as dibutyl phthalate is introduced into vessel 10 so as to cover the coils 36, 37 of the transformer.

The backing pump 38 is started up and after a suitable forevacuum has been attained within vessel 10, chamber 41 and pump body 32, pump 16 is started up. Valve 19 may be adjusted until, with valves 27 and 30 open, a desired liquid pressure obtains in pipe 29, as indicated on gauge 28. 5 to 50 lbs./square inch is a convenient range from which to select a working pressure.

Liquid will now be emitted by nozzle assembly 34 which liquid will return by gravity to vessel 10 and eventually will be recirculated through pump 16. An inspection window (not shown) may be provided in the wall of vessel 10 for observation of returning liquid.

Finally the primary winding 36 of the transformer may be energised, causing a heavy secondary current to flow through and heat conduit 33.

Conduit 33 then acts as a flash boiler and discharges vapourized working fluid to nozzle assembly 34. Vapour stream pumping action is then initiated, producing a high vacuum in any suitable closed system which may be connected to flange 35.

Vapourised pumping fluid eventually condenses on the inner surface of body 32 and the

condensate returns by gravity to vessel 10. The working fluid passing through the jacket under pressure from pipe 29 effectively maintains the jacket at a sufficiently low temperature for efficient condensing action and is itself preheated prior to passing into the flash boiler constituted by conduit 33.

The boiler may of course supply more than one jet disposed in cascade or parallel.

The nozzle assembly preferably exerts a restrictive action on the vapour to maintain pressure in the boiler.

In an alternative embodiment of the invention (Fig. 4), a flash boiler has a vertical cylindrical copper body 50 doubly flared at its lower end forming a nozzle 51 of conical annular form. Projecting from annular nozzle 51 are passageways 52 communicating with a central cavity 53 formed as a lower portion of an axial bore in the body 50. This bore extends for approximately half the height of the body, for the remainder of which height it is counterbored to receive a loose cup 54. One or more passageways 49 provide communication between cavity 53 and cup 54. In the base of cup 54 a valve seating 55 is formed coaxial with body 50.

A valve head formed at the upper end of a needle valve spindle 56 coacts with seating 55. A bobbin-shaped member 57 has a lower flange threadedly attached to the upper end of body 50. A top flange 58 of member 57 is conical and serves as a low pressure jet cowl. Passageways 48 are formed in the cylindrical part of member 57 near the top thereof, below flange 58. Depending from the centre of the upper end of member 57 is a rod 59 supporting a downwardly concave deflector 60 coaxial with body 50. Surrounding the outside of body 50 and electrically insulated therefrom by mica or ceramic sleeve 61 is a spiral heating coil 62 connected at its opposite ends to electrical conductors 63 and 64 respectively.

Formed integral with cup 54 is a downwardly extending hollow portion 65 forming a cooling chamber 66 for the valve head on spindle 56 and complementary seating 55. Communicating with chamber 66 is a fluid inlet conduit 67 arranged diametrically opposite a fluid outlet conduit 68.

The assembly is suitably positioned coaxially within a cooled conical condensing body 69, to the upper end of which is connected a system to be evacuated. A forevacuum connection (not shown) is provided near the lower end of body 69.

In operation working fluid is supplied under pressure by way of conduit 67 to the space 66. Thence a jet of liquid impinges on the inner and lower surface of deflector 60, and then passes downwardly on to the sides and bottom of cup 54. This cup is heated from body 50 which in turn is heated by spiral 62. A suitable current, preferably high amperage at low voltage, is passed through spiral 62 from conductors 63 and 64 to raise the temperature of cup 54 to a temperature sufficient to vapourise working fluid directed into said cup. Vapour generated in cup 54 passes downwardly through passageways 49 into cavity 53 and thence through passageways 52 issuing in a stream through nozzle 51. At the same time part of the vapour passes upwardly through the centre of member 57 and issues by way of passageways 48 and are deflected downwardly in a jet by means of the cowl formed by flange 58.

The vapours from both nozzles, after exerting pumping action are condensed on the inner surface of condensing body 69. The condensate and

excess liquid passing out from cooling chamber 66 through conduit 68 is collected and eventually recirculated and fed into conduit 67 for further action in the manner described.

I claim:

1. A high vacuum pump adapted to evacuate closed systems to low absolute pressures comprising in combination a closed chamber having an inlet for gases to be entrained, a vapour stream nozzle located near one end of the chamber and directed towards the opposite end of the chamber, means for cooling at least part of the walls of said chamber, a collecting and separating means for liquid and entrained gases at the end of the chamber opposite to the nozzle, said collecting and separating means containing a low vapour pressure organic liquid, an electrically heated flash boiler for heating and vapourising collected liquid, means for compressing such collected liquid, means for conveying compressed liquid to the flash boiler, means for conveying heated and vapourised liquid from said flash boiler to said nozzle, and an exhaust port for removing the entrained gases from the collecting and separating means.

2. A high vacuum pump adapted to evacuate closed systems to low absolute pressures comprising in combination a closed chamber having an inlet for gases to be entrained, a vapour stream nozzle located near one end of the chamber and directed towards the opposite end of the chamber, means for cooling at least part of the walls of said chamber, a collecting and separating means for liquid and entrained gases at the end of the chamber opposite to the nozzle, said collecting and separating means containing a low vapour pressure organic liquid, an electrically heated flash boiler within the chamber for heating and vapourising collected liquid, means for compressing such collected liquid, means for conveying compressed liquid to the flash boiler, means for conveying heated and vapourised liquid from said flash boiler to said nozzle, and an exhaust port for removing the entrained gases from the collecting and separating means.

3. A high vacuum pump adapted to evacuate closed systems to low absolute pressures comprising in combination a closed chamber having an inlet for gases to be entrained, a nozzle located within the chamber and directed towards one end of the chamber, means for cooling at least part of the walls of said chamber, a collecting and separating means for liquid and entrained gases at the said end of the chamber, said collecting and separating means containing a low vapour pressure organic liquid, an electrically heated flash boiler for vapourising collected liquid, means for compressing such collected liquid, means for conveying compressed liquid to the flash boiler, means for conveying vapourised liquid from said flash boiler to said nozzle, and an exhaust port for removing the entrained gases from the collecting and separating means.

4. A high vacuum pump adapted to evacuate closed systems to low absolute pressures comprising in combination a closed chamber having an inlet for gases to be entrained, a nozzle located near one end of the chamber and directed towards the opposite end of the chamber, means for cooling at least part of the walls of said chamber, a collecting and separating means for liquid and entrained gases at the end of the chamber opposite to the nozzle, said collecting and separating means containing a low vapour pressure organic liquid, an electrically heated

flash boiler for vapourising collected liquid, means for compressing such collected liquid, means for conveying compressed liquid to the flash boiler, means for conveying vapourised liquid from said flash boiler to said nozzle, and a forevacuum connection for removing the entrained gases from the collecting and separating means.

5. A high vacuum pump adapted to evacuate closed systems to low absolute pressures comprising in combination a closed chamber having an inlet for gases to be entrained, a nozzle within the chamber, and directed towards one end of the chamber, means for cooling at least part of the walls of said chamber, a collecting and separating means for liquid and entrained gases at the end of the chamber opposite to the nozzle, said collecting and separating means containing a low vapour pressure organic liquid, an electrically heated flash boiler for vapourising collected liquid disposed within the chamber adjacent the nozzle, means for compressing such collected liquid, means for conveying compressed liquid to the flash boiler, means for conveying vapourised liquid from said flash boiler to said nozzle, and a forevacuum connection for removing the entrained gases from the collecting and separating means.

6. A high vacuum pump adapted to evacuate closed systems to low absolute pressures comprising in combination a closed chamber having an inlet for gases to be entrained, a nozzle located near one end of the chamber and directed towards the opposite end of the chamber, means for cooling at least part of the walls of said chamber, a collecting and separating means for liquid and entrained gases at the end of the chamber opposite to the nozzle, said collecting and separating means containing a low vapour pressure organic liquid, a flash boiler constituted by a coiled conduit adapted to be heated by passing a high amperage electric current therethrough for vapourising collected liquid, means for compressing such collected liquid, means for conveying compressed liquid to the flash boiler, means for conveying vapourised liquid from said flash boiler to said nozzle, and a forevacuum connection for removing the entrained gases from the collecting and separating means.

7. A high vacuum pump adapted to evacuate closed systems to low absolute pressures comprising in combination a closed chamber having an inlet for gases to be entrained, a nozzle located near one end of the chamber and directed towards the opposite end of the chamber, means for cooling at least part of the walls of said chamber, a collecting and separating means for liquid and entrained gases at the end of the chamber opposite to the nozzle, said collecting and separating means containing a low vapour pressure organic liquid, a flash boiler constituted by a conduit adapted to be heated by passage of a high amperage electric current therethrough for vapourising collected liquid, said flash boiler being disposed within said chamber, means for compressing such collected liquid, means for conveying compressed liquid to the flash boiler, means for conveying vapourised liquid from said flash boiler to said nozzle, and a forevacuum connection for removing the entrained gases from the collecting and separating means.

8. In a vapour stream vacuum pump, a pump

body including a chamber having walls at least partially cooled and an inlet for gases to be entrained, an electrically heated flash boiler disposed within the chamber, means for supplying a compressed organic liquid of low vapour pressure to said flash boiler, and a nozzle arranged within the chamber for emitting a vapour stream capable of entraining gases to be pumped and adapted to be supplied with vapourised working fluid from said flash boiler.

9. In a vapour stream vacuum pump, a pump body including a chamber having walls at least partially cooled and an inlet for gases to be entrained, an electrically heated flash boiler disposed within the chamber and constituted by a conduit heated by passage of a high amperage electrical current therethrough, means for supplying a compressed organic liquid of low vapour pressure to said flash boiler, and a nozzle arranged within the chamber for emitting a vapour stream capable of entraining gases to be pumped and adapted to be supplied with vapourised working fluid from said flash boiler.

10. In a vapour stream vacuum pump a pump body including a chamber having walls at least partially cooled and an inlet for gases to be entrained, a flash boiler constituted by a metal tube having two ends, means for passing an electrical current through said tube to effect heating thereof, means for supplying a compressed organic liquid to one end of said tube, and a nozzle arranged within the chamber and connected to the other end of said tube for emitting a vapour stream capable of entraining gases to be pumped.

11. An arrangement for evacuating a vessel, comprising a high vacuum connection on said vessel, a backing pump, a conduit length extending between said backing pump and said high vacuum connection and sloping downwards towards said backing pump, a unitary flash boiler and nozzle disposed within said conduit length and directed away from said high vacuum connection, working fluid storage means, means for supplying working fluid to said unitary flash boiler and nozzle, and means for returning condensate of working fluid discharged through said nozzle to said storage means.

12. In a vapour stream vacuum pump, a pump body including a chamber having walls at least partially cooled and an inlet for gases to be entrained, a flash boiler within said chamber and constituted by a metal tube having two ends, means for passing an electrical current through said tube to effect heating thereof, means for supplying a compressed organic liquid to one end of said tube, and a nozzle arranged within the chamber and connected to the other end of said tube for emitting a vapour stream capable of entraining gases to be pumped.
